(57) **CLAIM**

The ornamental design for a wireless earphone set, as shown and described.

DESCRIPTION

FIG. 1 is a perspective view of a wireless earphone set showing my new design;

FIG. 2 is a front view of the left earphone and a rear view of the right earphone of FIG. 1;

FIG. 3 is a rear view of the left earphone and a front view of the right earphone of FIG. 1;

FIG. 4 is a right-side view of the left earphone and a left-side view of the right earphone of FIG. 1;

FIG. 5 is a left-side view of the left earphone and a right-side view of the right earphone of FIG. 1;

FIG. 6 is a top view of the wireless earphone set; and,

FIG. 7 is a bottom view thereof.

The broken lines in the drawings depict portions of the wireless earphone set that form no part of the claimed design.

1 Claim, 7 Drawing Sheets
